CLAIM

The ornamental design for a palm tree lamp, as shown and described.

DESCRIPTION

FIG. 1 is a perspective view of a palm tree lamp.

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken line disclosure of both the base and palm leaves represent portions of the lamp which form no part of the claimed design.
